UNITED STATES PATENT OFFICE.

LOUIS F. NAFIS AND MABEL SILLER NAFIS, OF EVANSTON, ILLINOIS.

COLOR-COMPARING ROD.

1,275,723.

Specification of Letters Patent. Patented Aug. 13, 1918.

Application filed February 1, 1918. Serial No. 214,807.

To all whom it may concern:

Be it known that we, LOUIS F. NAFIS and MABEL SILLER NAFIS, both citizens of the United States, and both residing at Evans-
ton, in the county of Cook and State of Illinois, have jointly invented new and useful Improvements in Color-Comparing Rods, of which the following is a full, clear, concise, and exact description, reference being had 10 to the accompanying drawing, forming a part of this specification.

Our invention relates to rods for comparing the color of various substances for various purposes.

15 One particular use for which the invention is intended is to procure uniformity of color of butter for the market. Others are to carry out certain tests to determine, say, the relative amounts of salt in butter 20 and of acid in milk, cream or whey, and the like.

In all such uses it is impossible for the operators to carry in mind the exact shade or shades required. Difficulty is also experienced in controlling the exact amount of added ingredients to produce a certain shade. Our invention provides unvarying shades of color in convenient and satisfactory form for comparison purposes, so that 30 it is unnecessary to charge the mind therewith, and a plurality of graduated shades so that if the exact shade of a color desired in the product has not been obtained, the operator can tell by comparison with the 35 various shades whether or not an allowable variation has been obtained.

The color comparing rod of our invention is durable and sanitary. It is readily kept clean and the colors are protected against 40 contact with the material compared or other external matter and against atmospheric action. It is simple in construction, comparatively cheap to manufacture, convenient to manipulate and satisfactory to operate. 45 Other objects and advantages will appear from the detailed description and claims to follow.

In the drawings, in which several embodiments of our invention are shown—

50 Figure 1 is a perspective view showing one embodiment of our invention in use for comparing the color of butter;

Fig. 2 is a side elevation of the same;

55 Fig. 3 is a cross-section of the butter color comparison rod on the line 3—3 of Fig. 2;

Fig. 4 is a longitudinal section of a rod having a different color producing means; and

Fig. 5 is a similar view showing still 60 a different way of providing the colors.

Referring now to Figs. 1 to 3, the instrument which we term a color comparing rod comprises a piece of cylindrical glass tubing 10 which may be about the size shown in Fig. 65 2, i. e., about eight inches long, hermetically sealed at both ends, and a roll of paper 11 fitting snugly inside the glass tube and extending substantially from one end to the other of the tube, enough space being left 70 at the ends so that the paper will not scorch or burn when the ends of the tube are sealed, the roll of paper being provided, on its outer surface, with a plurality of shades of color, in this instance four different standard shades of yellow 12, 13, 14 and 15, for comparing butter colors. These standard colors may range from that corresponding 75 to very pale butter, indicated at 12, to the darker color of natural June butter, indicated at 15. If desired, the spaces of different color may be separated by narrow uncolored spaces indicated at 16. The upper end of the paper roll may be left 80 blank or uncolored and suitable indicia 85 printed thereon if desired, such as directions for use, the name of the maker, etc.

The roll of paper is of such size that it extends completely around the inside of the glass tube, and in fact its edges overlap 90 slightly, as indicated in Fig. 3. The natural resiliency of the paper tends to make it unfold, and therefore the outer face of the paper is pressed outwardly and snugly against the inside of the glass tube. By 95 this construction the colors are clearly visible through the walls of the tube no matter in what position the tube is held. The size and shape of the tube are such that it can be easily grasped and manipulated.

100 The different colors shown as standard may be given distinguishing designations, such as A, B, C, D, and these designations may be adopted by the trade to indicate the various colors.

105 One method of using the butter color rod is as follows: If it is desired to determine which of the standard colors of the rod is nearest to a quantity of butter which is to be compared, the operator will get a sample 110 plug 17 of the butter on a trier, indicated at 17^a, Fig. 1, and hold this plug of butter

close to the rod, bringing it adjacent the various standard colors as in Fig. 1, until he decides which standard color is closest to the color of the sample. In the creamery man's case, if he finds that the sample is not the shade required, he can put in a greater or less proportion of coloring matter until he gets a sample which is the required shade. In the case of a dealer, he can decide whether the butter which he is considering is the shade which he wants, or can determine to what market it would be best to send it. These rods are intended to be used as a basis of comparison with finished butter at a temperature of about 40 to 50 degrees Fahrenheit, that being the temperature at which it is usually kept, and the warmer the butter the darker its shade.

The rod, of course, may have any desired number of colors or shades of color. For some uses two only may be preferable. For example, in making the salt and acidity tests above mentioned, by providing the rods with a minimum and a maximum shade in each, between which it is safe to base the complete neutralization of the sample being tested, the operator is not obliged to add the exact amount of neutralizer necessary to produce a certain color. He has certain limits between which it is safe to work. In these acid test comparison rods, also, the colors are different shades of pink, while in the salt test comparison rods the colors are different shades of reddish brown.

The glass tube, being hermetically sealed at both ends, protects the paper roll and the colors on the paper roll from atmospheric action and excludes dirt and moisture. The tube, being of glass and perfectly smooth, without any pockets or depressions, does not soon become dirty, and when it does it can be easily washed. It prevents the grease from coming into contact with the paper, which not only would be unsanitary but might affect the colors. The glass does not absorb the grease, and the rod may even be inserted in the butter, if desired, without harm to the rod or butter. In carrying out the acidity and salt tests referred to, the comparison rods are conveniently used as stirring rods to thoroughly mix the ingredients to be tested and compared with the colors in the rods.

Fig. 4 shows a similar rod but with the different colors 12^a, 13^a, 14^a, etc., formed by

suitably colored powder or granular material, such, for example, as sand, filling the tube 10, and with the divisions 16^a made of cotton wadding, cork or other desired substance to keep the various shades separated. 60

Fig. 5 shows a similar rod also, but in this instance the various colors 12^b, 13^b, 14^b, etc., are formed by colored liquid separated by divisions 16^b, preferably of cork. In fact, the colors may be made in any desired 65 or suitable way, though at present we prefer that of Fig. 2.

Various changes, alterations and modifications may be made in our invention without departing from the principle or scope 70 thereof and as defined or intended to be defined in the appended claims.

What we claim and desire to secure by Letters Patent is—

1. A color comparing rod comprising a 75 hand rod having a plurality of colors at different points of its length and separately visible for comparison purposes.
2. A color comparing rod comprising a glass rod having a plurality of colors at 80 different points of its length and visible from the exterior.
3. A color comparing rod comprising a transparent rod, and a plurality of separate colors therein and visible through said rod. 85
4. A color comparing rod comprising a glass tube, and a plurality of separate colors therein and visible through said tube.
5. A color comparing rod comprising a glass tube, a plurality of colors on paper in 90 said tube and visible at different points of its length from the exterior of the tube.
6. A color comparing rod comprising a hermetically sealed glass tube, and a roll of paper snugly fitting the inside surface of 95 said tube and provided with a plurality of colors visible from the exterior of the tube.
7. A butter color comparing rod comprising a hermetically sealed glass tube, and a plurality of butter colors in said tube. 100
8. A color-comparing rod comprising a hand-rod having its outer surface of a material non-soluble in water and having a plurality of colors at different points of its length and separately visible for comparison 105 purposes.

In witness whereof, we have hereunto subscribed our names.

MABEL SILLER NAFIS.
LOUIS F. NAFIS.
